(57) **ABSTRACT**

A limit switch may be provided with a switch body having a contact mechanism inside, and an operation unit connected to the switch body. The operation unit comprises an elastic part that energizes the operation lever from the first motion position towards the return position via the pivoting shaft and the first cam, and energizes the operation lever from the second motion position toward the return position via the pivoting shaft and the second cam, a first cam's pivoting restriction part that restricts the pivoting of the first cam in a first direction in which the operation lever moves from the return position to the second motion position, and a second cam's pivoting restriction part that restricts the pivoting to

(Continued)

the second cam in a second direction in which die operation lever moves from the return position to the first motion position.

LIMIT SWITCH

CROSS REFERENCE TO RELATED APPLICATIONS

This is the U.S. national stage of application No. PCT/JP2019/008633, filed on Mar. 5, 2019. Priority under 35 U.S.C. § 119(a) and 35 U.S.C. § 365(b) is claimed from Japanese Application No. 2018-046946 filed Mar. 14, 2018, the disclosure of which is also incorporated herein by reference.

TECHNICAL FIELD

The present disclosure relates to a limit switch.

BACKGROUND ART

Patent Document 1 discloses a limit switch provided with a housing in which a switch is housed. This limit switch includes a shaft extending from the outside to the inside of the housing and pivotably supported by the housing, and an arm that is connected to the end of the shaft on the outer side of the housing and can pivot the shaft.

PRIOR ART DOCUMENT

Patent Document

Patent Document 1: JP 2015-204223 A

SUMMARY OF INVENTION

Subjects to be Solved by the Invention

Some of the limit switches as described above are configured such that the arm extends in a direction orthogonal to the shaft, has one end in the extending direction of the arm fixed to the shaft, and can pivot among three positions in the circumferential direction with respect to the shaft (i.e., an intermediate return position where the limit switch is turned off, and a first motion position and a second motion position at both ends where the limit switch is turned on).

In such a limit switch, the arm is positioned at the return position by an energizing force of a coil spring or the like, so that the arm may swing at the return position instead of stopping immediately, and it may not be possible to accurately determine the return position. In this case, the return position varies for each limit switch, and it may not be possible to accurately operate the limit switch.

An object of the present disclosure is to provide a limit switch that can be operated accurately.

Means for Solving the Subjects

An example of the limit switch of the present disclosure includes:

a switch body having a contact mechanism inside, and an operation unit connected to the switch body.

The operation unit includes

a housing body connected to the switch body,

a pivoting shaft extending from an outside of the housing body to an inside of the housing body and pivotable around an extending direction of the pivoting shaft,

a bearing that is provided in the housing body and pivotably supports the pivoting shaft,

2

an operation lever that is connected to the pivoting shaft outside the housing body, and is pivotable together with the pivoting shaft between an intermediate return position disposed at intervals in a circumferential direction with respect to the extending direction of the pivoting shaft and each of a first motion position and a second motion position at both ends,

an annular first cam that is connected to the pivoting shaft inside the housing body, and includes a first transmitter pivoting together with the pivoting shaft to turn on and off the contact mechanism when the operation lever pivots from the return position to the first motion position, the first transmitter not pivoting together with the pivoting shaft when the operation lever pivots from the return position to the second motion position, the first cam permitting the pivoting of the pivoting shaft when the first transmitter does not pivot,

an annular second cam that is connected to the pivoting shaft with a gap from the first cam in the extending direction of the pivoting shaft and disposed symmetrically with the first cam with respect to the pivoting shaft inside the housing body, and includes a second transmitter pivoting together with the pivoting shaft to turn on and off the contact mechanism when the operation lever pivots from the return position to the second motion position, the second transmitter not pivoting together with the pivoting shaft when the operation lever pivots from the return position to the first motion position, the second cam permitting the pivoting of the pivoting shaft when the second transmitter does not pivot,

an elastic part that is provided inside the housing body, energizes the operation lever from the first motion position toward the return position via the pivoting shaft and the first cam, and energizes the operation lever from the second motion position toward the return position via the pivoting shaft and the second cam,

a first cam's pivoting restriction part that is provided inside the housing body, and restricts the pivoting of the first cam in a first direction in which the operation lever moves from the return position to the second motion position, and

a second cam's pivoting restriction part that is provided inside the housing body, and restricts the pivoting to the second cam in a second direction in which the operation lever moves from the return position to the first motion position.

Effects of the Invention

According to the limit switch, the operation unit includes: an elastic part that energizes the operation lever from the first motion position toward the return position via the pivoting shaft and the first cam, and energizes the operation lever from the second motion position toward the return position via the pivoting shaft and the second cam; a first cam's pivoting restriction part that restricts the pivoting of the first cam in a first direction in which the operation lever moves from the return position to the second motion position; and a second cam's pivoting restriction part that restricts the pivoting of the second cam in a second direction in which the operation lever moves from the return position to the first motion position. The elastic part, the first cam's pivoting restriction part, and the second cam's pivoting restriction part can reduce the swing of the operation lever at the return position to immediately stop the operation lever at the return position. As a result, it is possible to achieve the

limit switch that can reduce the variation of the return position of the operation lever and operate accurately.

BRIEF DESCRIPTION OF DRAWINGS

FIG. 1 is a perspective view illustrating a limit switch according to an embodiment of the present disclosure.

FIG. 2 is a perspective view illustrating an operation unit in a state where an operation lever of the limit switch in FIG. 1 has been removed.

FIG. 3 is a sectional view taken along line in FIG. 2.

FIG. 4 is a perspective view illustrating the operation unit in a state where a housing and an operation lever of the limit switch in FIG. 1 have been removed.

FIG. 5 is a sectional view taken along line V-V in FIG. 2.

FIG. 6 is a sectional view taken along line VI-VI in FIG. 4.

FIG. 7 is a sectional view taken along line VII-VII in FIG. 4.

FIG. 8 is a sectional view taken along line VIII-VIII in FIG. 2.

FIG. 9 is a front view illustrating a first modification of the limit switch in FIG. 1.

FIG. 10 is a sectional view taken along line in FIG. 2, illustrating a second modification of the limit switch in FIG. 1.

FIG. 11 is a sectional view taken along line VIII-VIII in FIG. 2, illustrating a third modification of the limit switch in FIG. 1.

MODES FOR CARRYING OUT THE INVENTION

Hereinafter, an example of the present disclosure will be described with reference to the accompanying drawings. In the following description, terms indicating specific directions or positions (e.g., terms including "up," "down," "right," and "left,") will be used as necessary, but the use of those terms is to facilitate understanding of the present disclosure with reference to the drawings, and the technical scope of the present disclosure is not limited by the meanings of those terms. The following description is essentially mere illustration and does not intend to restrict the present disclosure, its application, or its use. Further, the drawings are schematic, and the ratio of each dimension, or the like, does not necessarily match an actual one.

As illustrated in FIG. 1, a limit switch 1 according to an embodiment of the present disclosure is provided with a switch body 2 having a contact mechanism (not illustrated) inside, and an operation unit 3 detachably connected to the switch body 2.

As illustrated in FIG. 1, the switch body 2 has a hollow, substantially rectangular parallelepiped shape, and the operation unit 3 is connected to one of the side surfaces facing each other in the longitudinal direction (i.e., the upper surface in FIG. 1).

As illustrated in FIG. 1, the operation unit 3 includes: a housing 10; a pivoting shaft 20 extending from the outside of the housing 10 to the inside of the housing 10 and pivotable around the extending direction of the pivoting shaft 20; a bearing 30 (cf. FIG. 3) that is provided in the housing 10 and pivotably supports the pivoting shaft 20; and an operation lever 40 connected to the pivoting shaft 20 outside the housing 10.

As illustrated in FIG. 2, the housing 10 includes a hollow, substantially cubic housing body 11 connected to the switch body 2, and a peripheral wall 12 provided on one surface of

the housing body 11. The housing body 11 is provided with the bearing 30, and the pivoting shaft 20 extending from the outside of the housing body 11 to the inside of the housing body 11 is pivotably supported by the bearing 30. The peripheral wall 12 has a substantially cylindrical shape as an example, and surrounds the bearing 30 around the pivoting shaft 20 outside the housing body 11, as illustrated in FIG. 3.

As illustrated in FIG. 2, the pivoting shaft 20 has a substantially columnar shape and is configured to be pivotable around the extending direction thereof.

As illustrated in FIG. 3, the pivoting shaft 20 includes a protrusion 21 extending in a radial direction with respect to the pivoting shaft 20, and a recess 22 extending in a direction intersecting with (e.g., orthogonal to) the extending direction of the pivoting shaft 20 to house and hold the protrusion 21. The protrusion 21 is configured by a separate member from that of the pivoting shaft 20, and a part of the protrusion 21 is press-fitted into the recess 22 to be housed and held therein. Each of the protrusion 21 and the recess 22 is closer to the inside of the housing body 11 than a sealer 13 to be described later in the extending direction of the pivoting shaft 20, and the protrusion 21 is disposed to contact a pivoting restriction part 31 of the bearing 30 to be described later in the circumferential direction of the pivoting shaft 20. That is, the pivoting of the protrusion 21 around the pivoting shaft 20 is restricted by the pivoting restriction part 31 of the bearing 30 to define the pivoting range of the pivoting shaft 20.

As illustrated in FIG. 3, the bearing 30 is provided in the housing body 11, and the end of the housing body 11 is surrounded by the peripheral wall 12, the end being farther from the inside of the housing body 11. As illustrated in FIG. 4, the bearing 30 has a substantially cylindrical shape capable of pivotably supporting the pivoting shaft 20, and the pivoting restriction part 31 is provided at the end of the housing body 11, the end being farther from the inside of the housing body 11.

As illustrated in FIG. 5, the pivoting restriction part 31 is configured by a notch extending in the circumferential direction with respect to the pivoting shaft 20, and a first end 32 and a second end 33 in the circumferential direction with respect to the pivoting shaft 20 contacts the protrusion 21 of the pivoting shaft 20 to restrict the pivoting of the protrusion 21 of the pivoting shaft 20 around the pivoting shaft 20.

Note that the sealer 13 is provided within the peripheral wall 12 and at the end of the housing body 11, the end being farther from the inside than the bearing 30 in the extending direction of the pivoting shaft 20. The sealer 13 is configured by, for example, an oil seal, and seals the inside of the housing body 11.

As illustrated in FIG. 1, the operation lever 40 is disposed outside the housing body 11 and extends in a direction intersecting with (e.g., orthogonal to) the pivoting shaft 20. One end of the operation lever 40 in the extending direction thereof is connected to the pivoting shaft 20 so that the pivoting shaft 20 can be pivoted together with the pivoting of the operation lever 40. A roller 41 is provided at the other end of the operation lever 40 in the extending direction thereof so as to be pivotable around a pivoting axis L substantially parallel to the pivoting shaft 20.

As illustrated in FIG. 2, the operation lever 40 is configured to be pivotable between an intermediate return position P1 disposed at intervals in the circumferential direction with respect to the extending direction of the pivoting shaft 20 and each of a first motion position P2 and a second motion position P3 at both ends. In the limit switch 1, the return

position P1, the first motion position P2, and the second motion position P3 are disposed at an interval of about 90 degrees from each other in the circumferential direction around the pivoting shaft 20. In FIG. 2, a center line extending in the extending direction of the operation lever 40 is indicated by a dotted line.

As illustrated in FIG. 1, the operation lever 40 is located at the return position P1 in a state where no external force is applied. At this time, the operation lever 40 extends in a direction away from the switch body 2 along the longitudinal direction of the switch body 2 from the pivoting shaft 20. In a state where the operation lever 40 is located at the return position P1, the contact mechanism in the switch body 2 is off.

On the other hand, when an external force in the circumferential direction with respect to the pivoting axis L is applied to the operation lever 40, the operation lever 40 pivots together with the pivoting shaft 20 from the return position P1 to the first motion position P2 or the second motion position P3. By the pivoting of the operation lever 40, a first cam 61 and a second cam 62 to be described later, which are connected to the pivoting shaft 20, pivot and the contact mechanism in the switch body 2 is switched from off to on. That is, the operation lever 40 is configured to pivot the pivoting shaft 20 to turn on and off the contact mechanism.

As illustrated in FIG. 5, in the limit switch 1, when the operation lever 40 is located at the first motion position P2, the protrusion 21 of the pivoting shaft 20 contacts the first end 32 of the pivoting restriction part 31 of the bearing 30 in the circumferential direction with respect to the pivoting shaft 20. When the operation lever 40 is located at the second motion position P3, the protrusion 21 of the pivoting shaft 20 contacts the second end 33 of the pivoting restriction part 31 of the bearing 30 in the circumferential direction with respect to the pivoting shaft 20.

Further, as illustrated in FIG. 3, the operation unit 3 includes a pivoting shaft support 50. The pivoting shaft support 50 is provided around the pivoting shaft 20 at a position within the peripheral wall 12 and further away from the inside of the housing body 11 than the bearing 30 in the extending direction of the pivoting shaft 20.

Specifically, as illustrated in FIG. 4, the pivoting shaft support 50 is configured by a substantially annular second bearing 51 disposed over the circumference of the pivoting shaft 20. In a state where an external force along the extending direction of the pivoting shaft 20 (i.e., an external force F along the pivoting axis L illustrated in FIG. 1) is not applied to the operation lever 40, the second bearing 51 permits the pivoting of the pivoting shaft 20. In a state where the external force along the extending direction of the pivoting shaft 20 is applied to the operation lever 40, an end 52 on the outer side in the radial direction with respect to the pivoting shaft 20 contacts an inner circumferential surface 121 (illustrated in FIG. 3) of the peripheral wall 12 to support the pivoting shaft 20.

Further, as illustrated in FIG. 3, the operation unit 3 includes the first cam 61 and the second cam 62 that are each connected to the pivoting shaft 20 inside the housing body 11, and an elastic part 63 provided inside the housing body 11. The second cam 62 is disposed symmetrically with the first cam 61 with respect to the pivoting shaft 20.

As illustrated in FIG. 6, the pivoting shaft 20, to which the first cam 61, the second cam 62, and the elastic part 63 are connected, has substantially a semi-arc shape in cross section along the direction orthogonal to the extending direction of the pivoting shaft 20, and is formed with a locking surface

23 to which locking protrusions 613, 623 of the first cam 61 and a second cam 62 to be described later are locked.

As illustrated in FIG. 6, the first cam 61 includes a first transmitter 611 having an annular shape (including not only a complete annular shape but also a substantially annular shape provided with a notch), the first transmitter 611 pivoting together with the pivoting shaft 20 to turn on and off the contact mechanism when the operation lever 40 pivots from the return position P1 to the first motion position P2, the first transmitter 611 not pivoting together with the pivoting shaft 20 when the operation lever 40 pivots from the return position P1 to the second motion position P3. That is, the first transmitter 611 transmits to a drive component the power of the pivoting movement of the pivoting shaft 20 generated by the operation lever 40 pivoting from the return position P1 to the first motion position P2, to turn on and off the contact mechanism.

At a substantially center of the first cam 61, a substantially circular through-hole 612 is provided. On the inner circumferential surface of the through-hole 612, a locking protrusion 613 that locks with the locking surface 23 of the pivoting shaft 20 is provided. With the locking protrusion 613, when the operation lever 40 pivots in a second direction B from the return position P1 toward the first motion position P2, the first cam 61 pivots together with the pivoting shaft 20, while when the operation lever 40 is pivoted in a first direction A from the return position P1 toward the second motion position P3, the first cam 61 does not pivot together with the pivoting shaft 20 and permits the pivoting of the pivoting shaft 20 with respect to the first cam 61.

A first contact surface 614 is provided at the end of the first transmitter 611 on the downstream side in the second direction B where the operation lever 40 moves from the return position P1 toward the first motion position P2. As illustrated in FIG. 8, the first contact surface 614 is disposed so as to contact a first contact protrusion 71 to be described later in a state where the operation lever 40 is located at the return position P1. Further, on the opposite side of the first contact surface 614 of the first transmitter 611 with respect to the pivoting shaft 20, a spring locking part 615 for locking a first end 631 of the elastic part 63 is provided.

As illustrated in FIG. 7, the second cam 62 includes a second transmitter 621 having an annular shape (including not only a complete annular shape but also a substantially annular shape provided with a notch), the second transmitter 621 pivoting together with the pivoting shaft 20 to turn on and off the contact mechanism when the operation lever 40 pivots from the return position P1 to the second motion position P3, the second transmitter 621 not pivoting together with the pivoting shaft 20 when the operation lever 40 pivots from the return position P1 to the first motion position P2. That is, the second transmitter 621 transmits to a drive component the power of the pivoting movement of the pivoting shaft 20 generated by the operation lever 40 pivoting from the return position P1 to the second motion position P3, to turn on and off the contact mechanism.

At a substantially center of the second cam 62, a substantially circular through-hole 622 is provided. On the inner circumferential surface of the through-hole 622, a locking protrusion 623 that locks with the locking surface 23 of the pivoting shaft 20 is provided. With the locking protrusion 623, when the operation lever 40 pivots in the first direction A from the return position P1 toward the second motion position P3, the second cam 62 pivots together with the pivoting shaft 20, while when the operation lever 40 is pivoted in the second direction B from the return position P1

toward the first motion position P2, the second cam 62 does not pivot together with the pivoting shaft 20 and permits the pivoting of the pivoting shaft 20 with respect to the second cam 62.

A second contact surface 624 is provided at the end of the second transmitter 621 on the downstream side in the first direction A where the operation lever 40 moves from the return position P1 to the second motion position P3. As illustrated in FIG. 8, the second contact surface 624 is disposed so as to contact a second contact protrusion 72 to be described later in a state where the operation lever 40 is located at the return position P1. Further, on the opposite side of the second contact surface 624 of the second transmitter 621 with respect to the pivoting shaft 20, a spring locking part 625 for locking a second end 632 of the elastic part 63 is provided.

In the limit switch 1, the first contact surface 614 of the first cam 61 and the second contact surface 624 of the second cam 62 are each disposed on the same virtual plane orthogonal to the extending direction of the pivoting shaft 20.

As illustrated in FIG. 4, the elastic part 63 is configured by a coil spring, is disposed between the first cam 61 and the second cam 62, and is connected to the pivoting shaft 20 in a state where the first end 631 is locked to the spring locking part 615 of the first cam 61 and second end 632 is locked to the spring locking part 625 of the second cam 62. The elastic part 63 energizes the operation lever 40 from the first motion position P2 toward the return position P1 via the first cam 61 and the pivoting shaft 20, and energizes the operation lever 40 from the second motion position P3 toward the return position P1 via the second cam 62 and the pivoting shaft 20.

The operation unit 3 includes a first cam's pivoting restriction part and a second cam's pivoting restriction part each provided inside the housing body 11.

As shown in FIG. 8, the first cam's pivoting restriction part includes the first contact surface 614 of the first cam 61 and the first contact protrusion 71 connected to the housing body 11. The first contact protrusion 71 extends from the inside of the housing body 11 toward the first contact surface 614, and is configured to contact the first contact surface 614 when the operation lever 40 is at the return position P1, thereby restricting the pivoting of the first cam 61 in the first direction A in which the operation lever 40 moves from the return position P1 toward the second motion position P3.

As illustrated in FIG. 8, the second cam's pivoting restriction part includes the second contact surface 624 of the second cam 62 and the second contact protrusion 72 connected to the housing body 11. The second contact protrusion 72 extends from the inside of the housing body 11 toward the second contact surface 624, and is configured to contact the second contact surface 624 when the operation lever 40 is at the return position P1, thereby restricting the pivoting of the second cam 62 in the second direction B in which the operation lever 40 moves from the return position P1 toward the first motion position P2.

Note that each of the first contact surface 614 and the second contact surface 624 are formed by, for example, crushing the end of the first transmitter 611 on the downstream side in the first direction and the end of the second transmitter 621 on the downstream side in the second direction.

In the limit switch 1, the operation unit 3 includes the pivoting shaft support 50 that permits the pivoting of the pivoting shaft 20 with respect to the housing body 11 in a state of an external force along the extending direction of the pivoting shaft 20 being not applied to the operation lever 40, and contacts the peripheral wall 12 to support the pivoting

shaft 20 in a state of the external force along the extending direction of the pivoting shaft 20 being applied to the operation lever 40. The pivoting shaft support 50 can prevent the deformation of the pivoting shaft 20 due to an external force along the extending direction of the pivoting shaft 20, so that it is possible to achieve the limit switch 1 that is less likely to break down.

The pivoting shaft support 50 includes the annular second bearing 51 disposed over the circumference of the pivoting shaft 20. This makes it possible to prevent the deformation of the pivoting shaft 20 at an arbitrary position around the pivoting shaft 20 due to an external force along the extending direction of the pivoting shaft 20.

In the limit switch 1, the operation unit 3 includes the operation unit 3 detachably connected to the switch body 2, and in the operation unit 3, the pivoting shaft 20 includes the protrusion 21 that extends in the radial direction with respect to the pivoting shaft 20, and the bearing 30 includes the pivoting restriction part 31 that is disposed around the pivoting shaft 20 so as to be able to contact the protrusion 21, and restricts the pivoting of the protrusion 21 around the pivoting shaft 20. That is, the limit switch 1 restricts the pivoting of the pivoting shaft 20 not on the inside of the switch body 2 or the operation unit 3 but at the pivoting shaft 20 and the bearing 30, thereby restricting the pivoting of the operation lever 40. Thereby, even when an external force of a magnitude larger than expected is applied to the operation lever 40 from the pivoting direction thereof, it is possible to prevent the breakage of the drive component that turns on and off the contact mechanism, such as the cams 61, 62, and hence the limit switch 1 can be repaired simply by replacing the operation unit, for example. That is, it is possible to achieve the limit switch 1 that is easy to repair and has high convenience.

The operation unit 3 includes the cylindrical peripheral wall 12 surrounding the bearing 30 around the pivoting shaft 20 outside the housing body 11, and the sealer 13 that is disposed further away from the inside of the housing body 11 than the bearing 30 within the peripheral wall 12 and in the extending direction of the pivoting shaft 20 and seals the inside of the housing body 11. The protrusion 21 is disposed closer to the inside of the housing body 11 than the sealer 13 in the extending direction of the pivoting shaft 20. Hence it is possible to prevent the breakage of the drive component that turns on and off the contact mechanism units, such as the cams 61, 62 while sealing the inside of the operation unit 3, so that the convenience of the limit switch 1 can be further improved.

The pivoting shaft 20 is provided with the protrusion 21 extending outward in the radial direction from the pivoting shaft 20, and the bearing 30 is provided with the pivoting restriction part 31. This makes it possible to easily achieve the limit switch 1 easy to repair and having high convenience.

The protrusion 21 is configured by a separate member from that of the pivoting shaft 20, and the pivoting shaft 20 has the recess 22 extending in a direction intersecting with the extending direction of the pivoting shaft 20 to house and hold the protrusion 21. Thus, for example, by using a material with a higher degree of hardness than the pivoting shaft 20 to constitute the protrusion 21, the strength of the protrusion 21 can be increased.

In the limit switch 1, the operation unit 3 includes: the elastic part 63 that energizes the operation lever 40 from the first motion position P2 toward the return position P1 via the pivoting shaft 20 and the first cam 61 and energizes the operation lever 40 from the second motion position P3 to the

return position P1 via the pivoting shaft 20 and the second cam 62; the first cam's pivoting restriction part 614, 71 that restricts the pivoting of the first cam 61 in the first direction A in which the operation lever 40 moves from the return position P1 to the second motion position P3; and the second cam's pivoting restriction part 624, 72 that restricts the pivoting of the second cam in the second direction B in which the operation lever 40 moves from the return position P1 to the first motion position P2. The elastic part 63, the first cam's pivoting restriction part 614, 71 and the second cam's pivoting restriction part 624, 72 can reduce the swing of the operation lever 40 at the return position P1 to immediately stop the operation lever 40 at the return position P1. As a result, it is possible to achieve the limit switch 1 that can reduce the variation of the return position P1 of the operation lever 40 and operate accurately.

Further, the first cam's pivoting restriction part includes a first contact surface 614 provided at the end of the first transmitter 611 on the downstream side in the second direction B in which the operation lever 40 moves from the return position P1 toward the first motion position P2, and the first contact protrusion 71 that is connected to the housing body 11, and contacts the first contact surface 614 when the operation lever 40 is at the return position P1, to restrict the pivoting of the first cam 61 in the first direction A. The second cam's pivoting restriction part includes a second contact surface 624 provided at the end of the second transmitter 621 on the downstream side in the first direction A, and the second contact protrusion 72 that is connected to the housing body 11, and contacts the second contact surface 624 when the operation lever 40 is at the return position P1, to restrict the pivoting of the second cam 62 in the second direction B. This makes it possible to further reduce the swing of the operation lever 40 at the return position P1.

Note that the limit switch 1 is not limited to the above embodiment, but any configuration can be employed so long as the operation unit 3 includes the pivoting shaft support 50. For example, the protrusion 21 of the pivoting shaft 20, the pivoting restriction part 31 of the bearing 30, and the pivoting shaft support 50 may be omitted.

The pivoting shaft support 50 is not limited to being configured by the substantially annular second bearing 51 disposed over the circumference of the pivoting shaft 20. For example, as illustrated in FIG. 9, the pivoting shaft support 50 may be configured by a projection 53 extending outward in the radial direction from the pivoting shaft 20. As an example, a plurality of projections 53 are provided and arranged at intervals in the circumferential direction of the pivoting shaft 20. As described above, any configuration can be employed in the pivoting shaft support 50 so long as being a configuration where the pivoting shaft support 50 can permit the pivoting of the pivoting shaft 20 in a state where the external force F along the extending direction of the pivoting shaft 20 is not applied to the operation lever 40, and the pivoting shaft support 50 can contact the peripheral wall 12 to support the pivoting shaft 20 in a state where the external force along the extending direction of the pivoting shaft 20 is applied to the operation lever 40. That is, it is possible to achieve the limit switch 1 that is less likely to break down and has high flexibility in design.

The protrusion is not limited to the pivoting shaft 20, but for example, as illustrated in FIG. 10, the protrusion may be a protrusion 34 extending in a direction orthogonal to the pivoting shaft 20 from the inner circumferential surface of the bearing 30 facing the pivoting shaft 20. The pivoting shaft 20 in FIG. 10 is provided with a groove-shaped

pivoting restriction part 24 that can house the protrusion 34 of the bearing 30 and extends in the circumferential direction of the pivoting shaft 20.

The protrusion 21 is not limited to being configured by a separate member from that of the pivoting shaft 20 but may be integrally configured by the same member as that of the pivoting shaft 20.

The first cam's pivoting restriction part and the second cam's pivoting restriction part are respectively not limited to being configured by the contact surfaces 614, 624 and the contact protrusions 71, 72. For example, as illustrated in FIG. 11, the first cam's pivoting restriction part may be configured by a third contact surface 616 and a first elastic stopper 73, and the second cam's pivoting restriction part is configured by a fourth contact surface 626 and a second elastic stopper 74. The third contact surface 616 and the fourth contact surface 626 are respectively disposed between the first transmitter 611 and the second transmitter 621 so as to face the housing body 11 in the extending direction of the operation lever 40 (i.e., upward in FIG. 11) as viewed from the extending direction of the pivoting shaft 20 when the pivoting shaft 20 is located at the return position P1. The first elastic stopper 73 and the second elastic stopper 74 contact the third contact surface 616 and the fourth contact surface 626, respectively, and energize the respective cams 61, 62 in a direction orthogonal to the pivoting shaft 20.

For example, each of the first contact protrusion 71 and the second contact protrusion 72 may be configured by the same member as that of the housing body 11 or may be configured by a separate member (e.g., an elastic member such as rubber, a set screw, or a shim) from that of the housing body 11.

As described above, any configuration can be employed in each of the first cam's pivoting restriction part and the second cam's pivoting restriction part so long as being a configuration where the pivoting of the first cam 61 in the second direction B or the pivoting of the second cam 62 in the first direction A can be restricted. That is, it is possible to achieve the limit switch 1 that can accurately be operated and has high flexibility in design.

The peripheral wall 12 is not limited to being provided integrally with the housing 10 but may be provided separately. In this case, the peripheral wall 12 may be made of the same material as the housing body 11 or may be made of a different material therefrom.

In the above, various embodiments of the present disclosure have been described in detail with reference to the drawings. Finally, various aspects of the present disclosure will be described. In the following description, reference numerals will be added as examples.

A limit switch 1 according to the first aspect of the present disclosure includes:

a switch body 2 having a contact mechanism inside, and an operation unit 3 connected to the switch body 2.

The operation unit 3 includes
a housing 10 connected to the switch body 2,
a pivoting shaft 20 extending from an outside of the housing 10 to an inside of the housing 10 and pivotable around an extending direction of the pivoting shaft 20,
a bearing 30 that is provided in the housing 10 and pivotably supports the pivoting shaft 20,

an operation lever 40 that is connected to the pivoting shaft 20 outside the housing 10, and is pivotable together with the pivoting shaft 20 between an intermediate return position P1 disposed at intervals in a circumferential direction with respect to the extending direction of the pivoting

11

shaft 20 and each of a first motion position P2 and a second motion position P3 at both ends,

an annular first cam 61 that is connected to the pivoting shaft 20 inside the housing 10, and includes a first transmitter 611 pivoting together with the pivoting shaft 20 to turn on and off the contact mechanism when the operation lever 40 pivots from the return position P1 to the first motion position P2, the first transmitter 611 not pivoting together with the pivoting shaft 20 when the operation lever 40 pivots from the return position P1 to the second motion position P3, the first cam 61 permitting the pivoting of the pivoting shaft 20 when the first transmitter 611 does not pivot,

an annular second cam 62 that is connected to the pivoting shaft 20 with a gap from the first cam 61 in the extending direction of the pivoting shaft 20 and disposed symmetrically with the first cam 61 with respect to the pivoting shaft 20 inside the housing 10, and includes a second transmitter 621 pivoting together with the pivoting shaft 20 to turn on and off the contact mechanism when the operation lever 40 pivots from the return position P1 to the second motion position P3, the second transmitter 621 not pivoting together with the pivoting shaft 20 when the operation lever 40 pivots from the return position P1 to the first motion position P2, the second cam 62 permitting the pivoting of the pivoting shaft 20 when the second transmitter 621 does not pivot,

an elastic part 63 that is provided inside the housing 10, energizes the operation lever 40 from the first motion position P2 toward the return position P1 via the pivoting shaft 20 and the first cam 61, and energizes the operation lever 40 from the second motion position P3 toward the return position P1 via the pivoting shaft 20 and the second cam 62,

a first cam's pivoting restriction part 614, 71 that is provided inside the housing 10, and restricts the pivoting of the first cam 61 in a first direction A in which the operation lever 40 moves from the return position P1 to the second motion position P3, and

a second cam's pivoting restriction part 624, 72 that is provided inside the housing 10, and restricts the pivoting to the second cam 62 in a second direction B in which the operation lever 40 moves from the return position P1 to the first motion position P2.

According to the limit switch 1 of the first aspect, the elastic part 63, the first cam's pivoting restriction part 614, 71, and the second cam's pivoting restriction part 624, 72 can reduce the swing of the operation lever 40 at the return position P1 to immediately stop the operation lever 40 at the return position P1. As a result, it is possible to achieve the limit switch 1 that can reduce the variation of the return position P1 of the operation lever 40 and operate accurately.

In the limit switch 1 according to the second aspect of the present disclosure,

the first cam's pivoting restriction part includes

a first contact surface 614 provided at an end of the first transmitter 611 on a downstream side in the second direction B, and

a first contact protrusion 71 that is connected to the housing 10, and contacts the first contact surface 614 when the operation lever 40 is at the return position P1, to restrict the pivoting of the first cam 61 in the first direction A, and

the second cam's pivoting restriction part includes

a second contact surface 624 provided at an end of the second transmitter 621 on a downstream side in the first direction A, and

a second contact protrusion 72 that is connected to the housing 10, and contacts the second contact surface 624

12

when the operation lever 40 is at the return position P1 to restrict the pivoting of the second cam 62 in the second direction B.

According to the limit switch 1 of the second aspect, it is possible to further reduce the swing of the operation lever 40 at the return position P1.

In the limit switch 1 according to a third aspect of the present disclosure,

each of the first contact protrusion 71 and the second contact protrusion 72 is configured by a separate member from that of the housing 10.

According to the limit switch 1 of the third aspect, it is possible to achieve the limit switch 1 that can be accurately operated and has high flexibility in design.

In the limit switch 1 according to the fourth aspect of the present disclosure,

the first cam's pivoting restriction part includes

a first elastic stopper 73 that energizes the first cam 61 in a direction orthogonal to the pivoting shaft 20 in a state where the operation lever 40 is at the return position P1, to restrict the pivoting of the first cam 61 in the first direction A, and

the second cam's pivoting restriction part includes

a second elastic stopper 74 that energizes the second cam 62 in a direction orthogonal to the pivoting shaft 20 in a state where the operation lever 40 is at the return position P1, to restrict the pivoting of the second cam 62 in the second direction B.

According to the limit switch 1 of the fourth aspect, it is possible to achieve the limit switch 1 that can be accurately operated and has high flexibility in design.

By appropriately combining any of the various embodiments or modifications described above, the effects of the respective embodiments or modifications can be achieved. In addition, a combination of embodiments, a combination of examples, or a combination of an embodiment and an example is possible, and a combination of features in different embodiments or examples is also possible.

Although the present disclosure has been fully described in connection with the preferred embodiments with reference to the accompanying drawings, various variations and modifications will be apparent to those skilled in the art. It is to be understood that, so long as not departing from the scope of the present disclosure as set forth in the appended claims, the variations and modifications as thus described are included therein.

INDUSTRIAL APPLICABILITY

The limit switch of the present disclosure can be applied to, for example, an assembly line of an automobile or the like.

The invention claimed is:

1. A limit switch comprising:
 a switch body having a contact mechanism inside; and
 an operation unit connected to the switch body, wherein
 the operation unit comprises
 a housing connected to the switch body,
 a pivoting shaft extending from an outside of the housing
 to an inside of the housing and pivotable around an
 extending direction of the pivoting shaft,
 a bearing that is provided in the housing and pivotably
 supports the pivoting shaft,
 an operation lever that is connected to the pivoting shaft
 outside the housing, and is pivotable together with the
 pivoting shaft between an intermediate return position
 disposed at intervals in a circumferential direction with
 respect to the extending direction of the pivoting shaft
 and each of a first motion position and a second motion
 position at both ends,
 an annular first cam that is connected to the pivoting shaft
 inside the housing, and comprises a first transmitter
 pivoting together with the pivoting shaft to turn on and
 off the contact mechanism when the operation lever
 pivots from the return position to the first motion
 position, the first transmitter not pivoting together with
 the pivoting shaft when the operation lever pivots from
 the return position to the second motion position, the
 first cam permitting the pivoting of the pivoting shaft
 when the first transmitter does not pivot,

14

5 an annular second cam that is connected to the pivoting
 shaft with a gap from the first cam in the extending
 direction of the pivoting shaft and disposed symmetrically
 with respect to the first cam with respect to the pivoting
 shaft inside the housing, and comprises a second trans-
 mitter pivoting together with the pivoting shaft to turn
 on and off the contact mechanism when the operation
 lever pivots from the return position to the second
 motion position, the second transmitter not pivoting
 together with the pivoting shaft when the operating
 lever pivots from the return position to the first motion
 position, the second cam permitting the pivoting of the
 pivoting shaft when the second transmitter does not
 pivot,
 10 an elastic part that is provided inside the housing, energ-
 izes the operation lever from the first motion position
 toward the return position via the pivoting shaft and the
 first cam, and energizes the operation lever from the
 second motion position toward the return position via
 the pivoting shaft and the second cam,
 15 a first cam's pivoting restriction part that is provided
 inside the housing, and restricts the pivoting of the first
 cam in a first direction in which the operation lever
 moves from the return position to the second motion
 position, and
 20 a second cam's pivoting restriction part that is provided
 inside the housing, and restricts the pivoting of the
 second cam in a second direction in which the opera-
 tion lever moves from the return position to the first
 motion position, wherein
 25 the first cam's pivoting restriction part comprises
 a first contact surface provided at an end of the first
 transmitter on a downstream side in the second direc-
 tion, and
 30 a first contact protrusion that is connected to the housing,
 and contacts the first contact surface when the opera-
 tion lever is at the return position, to restrict the
 pivoting of the first cam in the first direction, and
 the second cam's pivoting restriction part comprises
 a second contact surface provided at an end of the second
 transmitter on a downstream side in the first direction,
 and
 35 a second contact protrusion that is connected to the
 housing, and contacts the second contact surface when
 the operation lever is at the return position to restrict the
 pivoting of the second cam in the second direction.
 40 2. The limit switch according to claim 1, wherein
 each of the first contact protrusion and the second contact
 protrusion is configured by a separate member from
 that of the housing.
 3. A limit switch comprising:
 45 a switch body having a contact mechanism inside; and
 an operation unit connected to the switch body, wherein
 the operation unit comprises
 a housing connected to the switch body,
 a pivoting shaft extending from an outside of the housing
 to an inside of the housing and pivotable around an
 extending direction of the pivoting shaft,
 50 a bearing that is provided in the housing and pivotably
 supports the pivoting shaft,
 an operation lever that is connected to the pivoting shaft
 outside the housing, and is pivotable together with the
 pivoting shaft between an intermediate return position
 disposed at intervals in a circumferential direction with
 respect to the extending direction of the pivoting shaft
 and each of a first motion position and a second motion
 position at both ends,
 55 an annular first cam that is connected to the pivoting shaft
 inside the housing, and comprises a first transmitter
 pivoting together with the pivoting shaft to turn on and
 off the contact mechanism when the operation lever
 pivots from the return position to the first motion
 position, the first transmitter not pivoting together with
 the pivoting shaft when the operation lever pivots from
 the return position to the second motion position, the
 first cam permitting the pivoting of the pivoting shaft
 when the first transmitter does not pivot,
 60 an annular second cam that is connected to the pivoting
 shaft with a gap from the first cam in the extending
 direction of the pivoting shaft and disposed symmetrically
 with respect to the first cam with respect to the pivoting
 shaft inside the housing, and comprises a second trans-
 mitter pivoting together with the pivoting shaft to turn
 on and off the contact mechanism when the operation
 lever pivots from the return position to the second
 motion position, the second transmitter not pivoting
 together with the pivoting shaft when the operating
 lever pivots from the return position to the first motion
 position, the second cam permitting the pivoting of the
 pivoting shaft when the second transmitter does not
 pivot,
 65 an elastic part that is provided inside the housing, energ-
 izes the operation lever from the first motion position
 toward the return position via the pivoting shaft and the
 first cam, and energizes the operation lever from the
 second motion position toward the return position via
 the pivoting shaft and the second cam,

15

an annular first cam that is connected to the pivoting shaft inside the housing, and comprises a first transmitter pivoting together with the pivoting shaft to turn on and off the contact mechanism when the operation lever pivots from the return position to the first motion position, the first transmitter not pivoting together with the pivoting shaft when the operation lever pivots from the return position to the second motion position, the first cam permitting the pivoting of the pivoting shaft when the first transmitter does not pivot,
 an annular second cam that is connected to the pivoting shaft with a gap from the first cam in the extending direction of the pivoting shaft and disposed symmetrically with the first cam with respect to the pivoting shaft inside the housing, and comprises a second transmitter pivoting together with the pivoting shaft to turn on and off the contact mechanism when the operation lever pivots from the return position to the second motion position, the second transmitter not pivoting together with the pivoting shaft when the operating lever pivots from the return position to the first motion position, the second cam permitting the pivoting of the pivoting shaft when the second transmitter does not pivot,
 an elastic part that is provided inside the housing, energizes the operation lever from the first motion position toward the return position via the pivoting shaft and the

5

10

15

20

25

16

first cam, and energizes the operation lever from the second motion position toward the return position via the pivoting shaft and the second cam,
 a first cam's pivoting restriction part that is provided inside the housing, and restricts the pivoting of the first cam in a first direction in which the operation lever moves from the return position to the second motion position, and
 a second cam's pivoting restriction part that is provided inside the housing, and restricts the pivoting of the second cam in a second direction in which the operation lever moves from the return position to the first motion position, wherein
 the first cam's pivoting restriction part comprises
 a first elastic stopper that energizes the first cam in a direction orthogonal to the pivoting shaft in a state where the operation lever is at the return position, to restrict the pivoting of the first cam in the first direction, and
 the second cam's pivoting restriction part comprises
 a second elastic stopper that energizes the second cam in a direction orthogonal to the pivoting shaft in a state where the operation lever is at the return position, to restrict the pivoting of the second cam in the second direction.
